Inventor
FRANK TAGER,
By his Attorney Julian J. Wittel

UNITED STATES PATENT OFFICE

FRANK TAGER, OF NEW YORK, N. Y.

EXCHANGEABLE RESILIENT HEEL

Application filed May 9, 1928. Serial No. 276,268.

This invention relates to resilient heels, commonly known as rubber heels, and has for its object to provide a heel of this character wherein the topmost layer of the same exposed to direct wear is made exchangeable.

Another object of this invention is to provide a device of the character mentioned which will be simple in construction, inexpensive to manufacture and wherein the exchangeable top layer may be easily applied or removed and exchanged by a new one by any ordinary person.

Other objects of the invention will be apparent as the specification of the same proceeds.

Features of the invention include a permanent layer secured to the heel of a shoe and made of hard rubber material, having a dovetail shaped ridge or web rising out of its center from one end of the same to a portion of its longitudinal center axis, and a softer resilient outer layer for the heel having a corresponding dovetail recess whereby it may be pushed over and be secured in position on said permanent layer. Further securing means may also be applied between the said two layers of my novel heel and corresponding rounded beads and grooves may also be arranged in the coacting sliding surfaces of the dovetail elements whereby they will be stronger bound to one another when in position.

In the drawings:

Fig. 1 is an elevation of my improved heel with portions of the shoe to which it is applied,

Fig. 2 shows a longitudinal section of the same,

Fig. 3 is a front elevation of my novel heel,

Fig. 4 is a bottom view of it, the exchangeable outside layer being only partly pushed into position,

Fig. 5 is a similar bottom view of a modification of my invention, and

Fig. 6 is a perspective view of the permanent or inside layer of my novel heel in said modified form, the said layer being shown in an inverted position for the sake of clearness.

Referring now more closely to the drawings, the numeral 10 indicates a portion of a shoe to which my novel heel is applied, my invention being represented in general by the character 11. The shoe has the regular sole 55 12 to which is secured the inner or stationary heel unit 13 of my device by nails, or by any other usual means. Said inner heel unit is preferably made of very hard rubber, but may be formed of any other suitable hard material which is adapted to retain its resistance and shape even under the strain of pressure exerted thereon while the exchangeable or outer softer rubber heel unit 14 of my invention is pushed into position thereon or pulled off 60 the same, as will be more fully explained presently. Said lower or inner heel unit 13 has also to be made of such material that while it will have frictional resistance between it and the outer rubber unit 14, it will be adapted to be formed to exact dimensions and to be finished by grinding or other means to a necessary exactness, if so desired.

Centrally the heel unit 13 is formed with an upstanding web or ridge 15 of a dovetail cross section, starting from the inner edge 16 of said unit and extending to the greater portion of the length of said unit 13 but not fully to its outer or heel end 17. A tapped bore 18 may also be provided in said web or ridge 70 15.

The outer heel unit 14 which is the rubber heel proper of my device and takes the place of the so called "rubber heels" now in use, is made of any of the customary softer rubber materials and has a dovetail recess 19 formed in the center thereof, corresponding in size, shape and length to the dovetail ridge 15 and intended to cooperate therewith.

A countersunk hole 20 is provided in the outer unit 14, being in alignment with the bore 18 when the two units are placed in a position to fully cover each other, as shown in the Figs. 1 to 3, and a sunken screw 21 may be threaded into the bore 18 to further secure the two units to one another.

When it is desired to provide a shoe with my improved elastic or rubber heel, the permanent or inner unit 13 of the same will first be secured to the heel portion 22 of the shoe,

the same being reduced in height to necessity, so as not to make an excessive high heel when the two units of my device will be applied thereto; or preferably, the unit 13 being secured directly to the rest of the shoe, my two units comprising the whole heel.

The said permanent or inner unit 13 will remain on the shoe as long as the same is worn or lasts and it even may thereafter be removed from the said shoe and transferred to another shoe of similar make and size.

On this stationary unit is applied the outer unit, or rubber heel proper 14, by simply pulling its recess 18 over the ridge 15 as will be understood. For a more secure binding action between the two and to insure the exchangeable layer 14 against wobbling, the recess may be somewhat narrower than the width of the rib, so that it will have to be forced thereon and the rubber material there-around compressed. When the two units are in exact alignment, screw 21 may be applied as an added fastening means between the two units.

After the outer unit or layer 14 is worn to the possible limit, it may be renewed by simply unscrewing the element 21, pulling the worn unit 14 off the web 15 and replacing it by an identical new one in the manner described.

The two sides of the web 15 as well as of the recess 18 may be in parallelism, or they may converge as shown, at 15' and 18' of Fig. 4, where the web and recess are shown as tapering towards the outer ends of the heel in order that the unit 14 may easier be pulled over onto the unit 13 or be pulled off therefrom.

In Figs. 5 and 6 a modified form of my invention is illustrated. Upper and inner units 14a and 13a are shaped generally in a similar manner to those described hereinabove, but the ridge 15a of the unit 13a shows a plurality of preferably semicircular grooves 23 in its two sides 24. The exchangeable unit 14 has a plurality of rounded beads 25 in the sides of its recess 18', corresponding in distance, size and number to the grooves 23. When the exchangeable unit 14a is forced over the inner unit 13a, as described hereinbefore, the beads with the adjacent portions of the unit 14a will be compressed and slide over the sides 24 of the ridge 15a until every bead will find its groove and the two units are firmly tied together in exact alignment.

This exchangeable rubber heel I consider broadly new, and hence, capable of taking many forms within the scope of my invention.

What I claim as new, is:

In an exchangeable resilient heel, having an inner permanent layer of comparatively hard material, and an outside removable layer of resilient material, a dovetail connec-

tion between the two layers, consisting of an undercut prismatic projection of outwardly inclined sides in the center of the permanent layer from the inner edge thereof to a distance towards the outer rounded end of the same but not reaching entirely thereto, and of a corresponding recess in said removable layer, the sides of the said projection and recess having rounded cooperative respective beads and grooves formed therein, for the purpose specified, said prismatic projection and said recess also being wider adjacent to the inner edges of their layers and converging rearwardly thereof.

Signed at New York, in the county of New York and State of New York this 28th day of April, A. D. 1928.

FRANK TAGER.
